CLAIM

The ornamental design for a bowl, as shown and described.

DESCRIPTION

FIG. 1 is a top perspective view of the design for a bowl, according to the disclosed subject matter.

FIG. 2 is a front side view of the bowl of FIG. 1, wherein a back side view, a left side view, and a right side view of the bowl are the same as the front side view.

FIG. 3 is a top view of the bowl of FIG. 1; and,

FIG. 4 is a bottom view of the bowl of FIG. 1.

The dash-dot-dash broken line in FIGS. 1-4 depicts a boundary; the dash-dot-dash broken line itself and the area within the boundary form no part of the claimed design.
